Patented Apr. 12, 1921.

Inventor
The Wisnipsky
By his Attorneys Edgar State Co.

UNITED STATES PATENT OFFICE.

IKE WISNIPOLSKY, OF BROOKLYN, NEW YORK.

MARKING DEVICE.

1,374,482.

Specification of Letters Patent. Patented Apr. 12, 1921.

Application filed November 29, 1919. Serial No. 341,396.

To all whom it may concern:

Be it known that I, IKE WISNIPOLSKY, a citizen of the United States, and residing at Brooklyn, in the county of Kings and State 5 of New York, have invented certain new and useful Improvements in Marking Devices, of which the following is a specification, such as will enable those skilled in the art to which it appertains to make and use the 10 same.

This invention relates to marking devices and particularly to devices of this class designed to be used in connection with button-hole making machines, button attaching machines and similar machines of this class for attaching devices of any kind or class to garment parts at spaced intervals; and the 15 object of the invention is to provide a device which may be readily attached to machines of the class specified and operated by said machines or a part thereof to mark on a garment part or sheet of fabric of any kind or class the place where buttonholes are to be formed and the place where buttons or 20 other attaching devices are to be secured; a further object of the invention being to provide a device of the class specified with adjustable means whereby the space between the buttonholes, buttons or other attaching 25 devices may be varied; and with these and other objects in view the invention consists 30 in a device of the class and for the purpose specified, constructed and operating as hereinafter described and claimed.

35 The invention is fully disclosed in the following specification, of which the accompanying drawing forms a part, in which the separate parts of my improvement are designated by suitable reference characters in 40 each of the views, and in which:

Figure 1 is a diagrammatic plan view of the work-bench or table of a buttonhole making machine and showing my improvement mounted in connection therewith;

45 Fig. 2 a partial section on the line 2—2 of Fig. 1; and,

Fig. 3 a partial section on the line 3—3 of Fig. 1.

In Fig. 1 of the drawing 5 represents a 50 work-bench or table upon which the bed-plate 6 of the buttonhole machine is secured. A plunger 7 is movable toward and from the bed-plate 6 and is provided with a head portion 8 with which a cutter blade 9 is detachably connected, said blade being held in place by a set screw 10. These parts of

the machine have been shown and described merely for the purpose of illustrating the use of my improved marking device 11, and it will be apparent that while I have shown this device in connection with a buttonhole making machine, I am not necessarily limited to this combination as the marking device may be used in connection with various other machines of a similar character.

The marking device 11 consists of a frame 12 preferably stamped from sheet metal and comprises end members 13 and 14 joined by a longitudinal member 15, having an elongated aperture 16 which extends approximately the full length thereof. The end member 13 is provided with an outwardly directed extension 17 which preferably extends at right angles to the part 13, as clearly shown in Fig. 1. The end members 13 and 14 of the frame are also joined by a shaft 18 upon which the frame 12 is rotatably mounted. The shaft 18 extends through the end member 14 of the frame as shown at 19 and a supporting arm 20 is secured to the extension 19 and is bent inwardly and downwardly and provided at its free end with a foot-piece 21 through which screws 22 are adapted to pass into the table 5 for securing the arm 20 in position. The arm 20 serves as a support for the frame 12.

Mounted on the extension 19 of the shaft 18 is a spiral spring 23, one end 24 of which operates in connection with the arm 20, while the other end 25 thereof operates in connection with the frame 12, or the end member 14 thereof to normally hold said frame in a raised or inoperative position. Slidably and adjustably mounted on the frame 12, which constitutes the main frame of the device, is a supplemental frame 26 which is also preferably composed of sheet metal, one end of which is fashioned into a loop 27 to engage the shaft 18, as clearly shown in Fig. 2, and the other end portion of which is bent at right angles as shown at 28, and said end portion is also bent into a spring loop 29 in which a pencil, crayon or the like 30 is adapted to be grasped. The loop 29 is sprung together by a bolt 31 to securely grasp the pencil 30 therein as clearly shown in Fig. 1.

Passed centrally through the supplemental frame 26 is a bolt 32 which also passes through the aperture 16 of the main frame 12, and this bolt is provided with a thumb nut 33, which serves to secure the supple-

mental frame in connection with the main frame in any desired position of adjustment. The longitudinal member 15 of the frame, or one part thereof, is preferably provided 5 with scale marks as shown at 34 in connection with which the supplemental frame 26 coöperates in order to set the marking member 30, either a pencil or crayon, in the desired position relative to a predetermined 10 part or mechanism of the machine in connection with which the marking device operates.

As previously stated, I have shown for illustration my improved marking device 11 mounted in connection with a button-hole 15 making machine and, in this use of the device, the frame 12 is preferably operated on the shaft 18 by the engagement of the head 35 of the set screw 10 of the machine with 20 the extension 17 on the side member 13 of said frame, as is clearly shown in Figs. 1 and 3, whereby in the downward movement of the plunger 7 to pass the cutter blade 9 through a strip of cloth or garment part 25 shown at 36 to finish the making of a button-hole in said garment part, the frame 12 will also be moved downwardly to bring the pencil, crayon or similar member 30, or the pointed end 37 thereof, into engagement 30 with the top face of said garment part at a predetermined distance from the cutter blade 9 to mark on said garment part the location of the next buttonhole which is to be made in said garment part. It will be 35 apparent that the supplemental frame 26 may be adjusted longitudinally of the frame 12 to bring the pencil or other device 30 at the desired distance from the cutter blade 9, and when once set in position it will remain 40 in such position until a different spacing between the buttonholes is desired.

It will be apparent that while I have shown my improved marking device as operated through a specific part by a specific 45 machine, my invention is not limited in this respect, as the marking device may be operated by any moving part of a buttonhole machine which will not interfere with the passage of a workpiece, namely, a garment 50 part or the like into and through the machine, but this also applies when the marking device is used in connection with other machines of a similar character to that shown herein, for illustration, and various changes 55 in and modifications of the construction and operation of the device herein shown and described may be made, within the scope of the appended claims, without departing

from the spirit of the invention or sacrificing its advantages. 60

Having fully described my invention, what I claim as new and desire to secure by Letters Patent, is:—

1. A marking device of the class described comprising a shaft, means for supporting said shaft, a main frame composed of sheet metal fashioned to form end members joined by a longitudinal member having an elongated aperture, said shaft passing through apertures in said end members for rotatably 70 supporting said main frame, a supplemental frame mounted on said shaft and adjustable longitudinally thereof and of the main frame, means passed through said supplemental frame and the longitudinal slot in 75 the main frame for securing said supplemental frame in connection with the main frame in different positions of adjustment, tensional means for holding the main and supplemental frames normally in a raised 80 position, and means on the supplemental frame for detachably and adjustably securing a marking element in connection therewith.

2. A marking device of the class described 85 comprising a shaft, means for supporting said shaft, a main frame composed of sheet metal fashioned to form end members joined by a longitudinal member having an elongated aperture, said shaft passing through 90 apertures in said end members for rotatably supporting said main frame, a supplemental frame adjustably mounted on the main frame and comprising a strip of sheet metal one end of which is looped to engage said 95 shaft, the other end portion being bent at right angles and provided with an open spring loop member adapted to detachably and adjustably support a marking element, means passed centrally through said supplemental frame and the longitudinal slot of 100 the main frame for securing said supplemental frame in connection with the main frame in different positions of adjustment, and tensional means for holding the main 105 and supplemental frames normally in a raised position.

In testimony that I claim the foregoing as my invention I have signed my name in presence of the subscribing witnesses this 110 25th day of November, 1919.

IKE WISNIPOLSKY.
